UNITED STATES PATENT OFFICE

SIMON E. SCHROEDER, OF NEWTON, IOWA, ASSIGNOR TO THE MAYTAG COMPANY, OF
NEWTON, IOWA, A CORPORATION OF DELAWARE

WASHING MACHINE

Application filed March 16, 1927. Serial No. 175,753.

This invention relates to washing machines, and more particularly to washing machines of the upright oscillator type, wherein the tub member is fashioned with a plurality of blade or baffle members upon the bottom thereof, the same being adapted to create a violent water action. One of the objects of the invention is in the provision of a washing machine of the upright oscillator type, the reciprocated tub member being fashioned with a plurality of blade or baffle members upon the bottom thereof, the same being fashioned in a manner to create a turbulent water action and therefore to cleanse the clothes content in a remarkably short time. Another object is in the provision of a washing machine of the type wherein a tub member is reciprocated by power mechanism, said tub member being fashioned with water-agitating means upon the bottom thereof, whereby the reciprocation of the tub and the action of the blades co-operate to cleanse the clothes in a very short time. Still another object is in the provision of an upright tub member, power means for reciprocating same, and blades disposed in the bottom of the tub, the side walls of the tub being free from obstruction, and a baffle disposed intermediate of the tub and projecting upwardly from the bottom thereof, providing not only a drain mechanism for the tub, but also means for preventing entangling of the clothes during the washing operation. A further object is in the provision of an upright tub member, power means for reciprocating same, said tub member being provided with a plurality of spaced blade members upon the bottom thereof, said blades being raised a sufficient distance from the bottom to create a violent water action and being fashioned in a manner to prevent excess wear upon the clothes during their violent reciprocation. A still further object lies in the provision of an upright tub member, power means for reciprocating same, said tub member having disposed upon the bottom portion thereof water-agitating means, said water-agitating means being raised sufficiently from the bottom thereof to create a violent water action, and thereby cleanse the clothes content in a remarkably short time. Other objects will appear in the following specification taken in connection with the annexed drawings, in which—

Fig. 1 is a side elevation, partially in cross-section, showing in detail the arrangement of parts of the washing machine; 60

Fig. 2 is a plan view thereof; 65

Fig. 3 is a cross-sectional view showing a modification of the tub member, or rather a modification of the blades disposed upon the bottom of the tub;

Fig. 4 is a plan view of Fig. 3; 70

Fig. 5 is a side elevation, partially in cross-section, showing in detail the arrangement of parts, and especially the construction of the tub portion, the same being a modification of the showing in Fig. 1;

Fig. 6 is a plan view of Fig. 5; 75

Fig. 7 is a cross-sectional view, showing in detail another modification of the upright oscillating tub and blade portions; and

Fig. 8 is a plan view of Fig. 7. 80

Referring to the drawings, in Fig. 1 there is shown in detail my upright oscillator type of washing machine, wherein a frame portion is shown at 10, securely attached, as at 11, to a supporting and housing portion 12, the same surrounding the tub and power means for the washer. Fixedly attached to the lower end of the housing 12, as at 13, are the plural leg portions 14, there being provided conventional connecting means 15 between same. A rim for the top of the housing 12 is shown at 16, the same being adapted to enclose a substantial part of the upper end of the washing machine, or rather, the tub member thereof. Secured, as at 17, to the support or framing structure 10, is a bearing portion 18, of substantial length and disposed vertically, as may be clearly seen in Fig. 1. This elongated bearing portion 18 provides a bearing surface both upon the inner and outer part of its upper surface. The plural reach members 19 have a central hub 20, which surrounds the upper portion of the bearing 18, there being disposed upon the outer ends of said reach members 100

friction pads 21, secured by means of members 22 to the before mentioned reach members.

A tub supporting and driving plate 23 is secured in any suitable manner to the bottom of the tub 24. This plate 23 has a centrally disposed and downwardly projecting stem 25, which is slidable within the portion 18, the same providing a support and bearing therefor, as well as a means for centering the tub. The connection between the driving plate 23 and the reach members lies in the before mentioned friction elements 21. This frictional driving means provides not only the driving connection between the tub and power means, but also a means for preventing vibration during such reciprocation. The tub is preferably constructed with the side wall curved inwardly as indicated at 32.

Means for reciprocating the reach members 19 is provided in the pitman 26, the same being connected to the reach members at one end and having the pivotal connection 27 at its other end with a crank 28. Means for rotating the crank 28 is provided in a vertical stub shaft 29, to which said crank is fixedly attached, as at 30, at its upper end. The vertical stub shaft is suitably supported in the supporting frame 10 at a point adjacent its upper end, and at its bottom in a bearing 31 formed in a suitably arranged gearing housing also attached to the housing 12 and support 10. Means for rotating the vertical stub shaft is provided in the worm gear 33 and an adjacent worm 34. A conventional pulley 35 is attached to the driving end of the worm and said pulley depends for its rotation upon a belt 35^a, the same being driven by the conventional electric motor 36.

The before mentioned downwardly projecting stem 25, which centers the tub 24, has an opening through its center portion, as shown at 37, said portion opening into a drain mechanism 38 adapted to carry off the water through the tub through the tube or outlet 39 to any point desired.

With respect to the tub 24, a plurality of blades or baffles 40 are disposed upon the bottom of the tub, said blades being raised a substantial distance from the bottom thereof and adapted to create a violent disturbance of the water contents during reciprocation of the tub. These blades or baffles operate in substantially the same manner as the blades upon a reciprocating disk in the well known type of washer, wherein the dolly portion is disposed upon the bottom and the blades project upwardly therefrom and are reciprocated in a manner to create a violent water action.

In the present instance, violent water action is not only created by the action of the upwardly projecting blades, but also by the reciprocation of the tub and it is apparent that the clothes content is continuously moved by the water action in a manner to

cleanse same as well as to be agitated by the blades reciprocating with the tub.

The blades 40 are rounded at their upper ends, as shown at 41, to prevent excessive wear upon the clothes content during reciprocation. In Figs. 1 and 2 the blades are shown merging with the wall of the tub at positions approximately corresponding with the curved portion 32, while the inner ends are rounded and project merely to a point adjacent the central portion of the tub. In other words, the outer extremities of the top edges of said blades are curved upwardly and inwardly and gradually merged into the contiguous portions of the side of the tub at positions below the plane of the upper end of said baffle member. The inner extremities of the top edges of the blades are extended downwardly to the bottom of the tub at positions spaced radially from said baffle member. In these figures, a vertically disposed baffle or sleeve 42 either forms a part of, or is attached to, the bottom of the tub, the same operating to support the drain mechanism which comprises a drain plug or valve 43^a adapted to seat in a drainage aperture in the bottom of the tub, a vertically disposed plug controlling member 44, and a manually operated screw or lug member 45 attached to the upper end of member 44 and adapted, by manual movement, to raise the drain plug from its seat and therefore permit the draining of the tub. Apertures 46 permit entrance of the water content in the tub to a point about the drain plug or valve 43^a.

It might be said at this point that the baffle or sleeve 42 not only acts as a means for supporting the tub drain mechanism, but also as a centrally disposed member of relatively small diameter for preventing entangling of the clothes content during reciprocation of the tub, or rather during washing operation.

In the remaining figures of the drawings, the washing machine structure and means for reciprocating the tub has not been changed, but merely the manner of baffling the tub has been disclosed in various manners. For instance, in Figs. 3 and 4, the blades 40^a do not merge with the side walls of the tub, but merely lie adjacent the bottom and merge with the stem 42.

In Figs. 5 and 6, the blades are exactly the same shape as those shown in Figs. 1 and 2 of the drawings, but the central stem has been removed and the drain opening has merely a threaded plug or valve 47 inserted therein. In this instance the draining of the tub is accomplished by removing the plug or valve 47.

In Figs. 7 and 8, the drain mechanism is provided in a conventional drain opening 48 and valve 49, said drain mechanism being disposed exteriorly of the tub and at such a point that the entire water content of the

tub is adapted to be drained therefrom by opening the valve.

In this instance, the blades 40^b not only merge with the sides of the tub, but also are merged at an intermediate point 50, as shown in Fig. 8. In this instance, also, there is no centrally disposed, upwardly projecting baffle to prevent entangling of the clothes or to support a drain mechanism.

Having described in detail the washing machine, and particularly the bladed tub portion, it might be said that the reach members 19 are reciprocated in the manner described herein, the same being of well known construction and devised, in the first instance, by the present applicant.

Although the present tub is disclosed as being round, nevertheless it is obvious that a tub fashioned either substantially rectangular in shape or with plural side portions, might similarly have disposed upon its bottom upwardly projecting blade members adapted to create a violent water action during reciprocation of the tub.

A removable cover is adapted to be placed upon the inwardly projecting ends 51 of the tub and it is apparent that the rim 16 may be removed and the tub portion manually removed by simple vertical lift. The side portions of the tub are flared slightly, as shown clearly at 52, and also the connection between the side portions and the bottom of the tub is an unobstructed curved portion 53.

It is thought from the above that the operation of the machine will be clear, and that the reciprocation of the tub will also cause reciprocation of the blade portions to create a violent water action and therefore a quick cleansing of the clothes content. The clothes are adapted to move in the path of the water disturbed by the upwardly projecting blade portions, and by the reciprocation of the tub itself, such movement being aided to some extent by the curvature of the tub wall near the bottom thereof. Said curvature also aids in directing flow of water to the drainage aperture in the bottom of the tub, so as to facilitate emptying of said tub.

What I claim is:

1. In a washing machine, a tub, a centrally located baffle member of relatively small diameter extending upwardly from the bottom of the tub, and a plurality of upstanding agitating blades extending upwardly from the bottom of the tub and disposed radially with respect to said baffle member, the outer extremities of the top edges of said blades being curved upwardly and inwardly and gradually merged into the contiguous portions of the sides of the tub at positions below the plane of the upper end of said baffle member.

2. In a washing machine, a tub, a centrally located baffle member of relatively small diameter extending upwardly from the

bottom of the tub, and a plurality of upstanding agitating blades extending upwardly from the bottom of the tub and disposed radially with respect to said baffle member, the inner extremities of the top edges of said blades being extended downwardly to the bottom of the tub at positions spaced radially from said baffle member, the outer extremities of the top edges of said blades being curved upwardly and inwardly and gradually merged into contiguous portions of the sides of the tub at positions below the plane of the upper end of said baffle member.

3. In a washing machine, a tub having the lower portion of its side wall curved inwardly and gradually merged into the bottom of the tub, a centrally located baffle member of relatively small diameter extending upwardly from the bottom of the tub, and a plurality of upstanding agitating blades also extending upwardly from the bottom of the tub and disposed radially with respect to said baffle member, the outer extremities of the top edges of said blades being curved upwardly and inwardly and gradually merged into contiguous portions of the sides of the tub.

4. In a washing machine, a tub having the lower portion of its side wall inwardly curved and merged into the bottom of the tub, a centrally located baffle member of relatively small diameter extending upwardly from the bottom of the tub, and a plurality of upstanding agitating blades extending upwardly from the bottom of the tub and disposed radially with respect to said baffle member, the inner extremities of the top edges of the blade being extended downwardly to the bottom of the tub at positions spaced radially from said baffle member, the outer extremities of the top edges of said blades being curved upwardly and inwardly and gradually merged into contiguous portions of the sides of the tub.

In testimony whereof, I have hereunto affixed my signature.

SIMON E. SCHROEDER.
